M. C. BRIGHT

VACUUM CONTROLLED FUEL SUPPLY SYSTEM

Filed Dec. 16, 1922

INVENTOR:
Martin C. Bright,
BY
E. J. Silvius,
ATTORNEY.

UNITED STATES PATENT OFFICE.

MARTIN C. BRIGHT, OF INDIANAPOLIS, INDIANA, ASSIGNOR TO BERNARD B. CARLIN,
OF CHICAGO, ILLINOIS.

VACUUM-CONTROLLED FUEL-SUPPLY SYSTEM.

Application filed December 16, 1922. Serial No. 607,306.

This invention relates generally to the lifting of liquid from one level or source of supply to a higher level by the action of vacuum or suction, and especially to a system whereby to supply internal-combustion engines with fuel when the source of supply is lower than the engine, as on a motor vehicle carrying a fuel reservoir or tank in a convenient position which usually is too low to permit liquid fuel to flow therefrom by force of gravity to the carburetor commonly arranged adjacent to the engine, and the invention relates more particularly to a vacuum tank and means whereby to control the supply of fuel through the tank to the engine.

An object of the invention is to provide an improved vacuum-controlled fuel-supply system of the above-mentioned character, and especially an improved vacuum tank and apparatus associated therewith for controlling the flow of the fuel into and out of the tank with ample volume to feed the carburetor of the engine.

Another object is to provide improvements in a vacuum tank of the character described in Letters Patent No. 1,374,983, granted to me April 19, 1921, more particularly with respect to controlling apparatus pertaining to the tank.

A further object is to provide an improved vacuum tank which shall be so constructed as to be compact and have means whereby vacuum shall be properly maintained and positively controlled to supply an adequate supply of fuel under varying conditions of operation, especially when a motor vehicle is ascending a hill when interruption of the supply of fuel might be disastrous, improvements of this character having been described but not claimed in my application for Letters Patent filed April 25, 1921, Serial No. 464,246.

A still further object is to provide buoyant-automatic vacuum-controlling means in vacuum tanks which shall be simple and adapted to operate reliably, and which shall be so constructed as to obviate the necessity of employing various mechanical devices in connection therewith which may be liable to become deranged and inefficient in operation, an aim being to provide an improved vacuum tank and controlling means therefor which shall be adapted to be manufactured

at small cost in large numbers principally by means of machinery, and which shall be durable and economical in use.

With the above-mentioned and other objects in view, the invention consists in a vacuum-controlled fuel-supply system having novel co-related features whereby to lift and to feed liquid, especially hydro-carbon; and, the invention consists also further in the novel parts, and in the combinations and arrangements of parts as hereinafter particularly described and further defined in the claims appended hereto.

Referring to the drawings, Figure 1 is a side elevation of the fuel-supply system, including an automobile engine or motor indicated in outline by broken lines; Fig. 2 is a vertical central section of the improved vacuum tank comprised in the fuel-supply system; Fig. 3 is a top plan of the vacuum tank, partially in section on the line III—III in Fig. 2; Fig. 4 is a reproduction of the upper portion of Fig. 2 on an enlarged scale, parts of the apparatus being shown in different positions; Fig. 5 is a fragmentary section on the line V—V in Fig. 4; and, Fig. 6 is a fragmentary reproduction of Fig. 4 slightly modified.

In the different figures of the drawings similar reference characters indicate corresponding elements or features of construction herein particularly referred to.

The fuel-supply system will be understood generally by reference to Fig. 1 in which the numeral 1 indicates the forward portion of an automobile body, 2 an internal-combustion engine, 3 the front of the engine housing or radiator, and 4 the intake manifold of the engine. Any suitable carburetor 5 may be employed, the same usually having a mixing tube 6 leading to and connected with the intake manifold, the lower portion of the carburetor having a suitable fuel inlet which may be a neck or conduit 7 to conduct the liquid fuel from a feed-reservoir or float chamber which for the purpose of the present invention may comprise a cylindrical body 8 and a bottom 9. A float 10 is arranged above the bottom and is guided preferably on a guide rod 11 secured to the bottom, the float having a valve stem 12 on its top which has a feed-valve 13 on its upper end.

The improved vacuum tank comprises a

cylindrical wall 14 having a bottom 15 which is secured to the body 8 to constitute a reservoir top, being provided with a duct 16 at the lower end of which is a valve seat 17 arranged to be engaged by the valve 13 to control the flow of fuel into the feed-reservoir. The vacuum tank has a head 18 on the wall and a plurality of chambers within it, a partition 19 being connected to the wall 14 and constituting the bottom of the upper one of the chambers. Preferably the wall 14 has an outwardly offset portion 20 below the bottom 19 so as to provide an annular top portion 21 extending about the wall 14. The bottom 19 constitutes the top of the lower one of the chambers and also the top of a middle chamber preferably arranged in the lower chamber, the middle chamber comprising a neck 22 which is connected to the partition 19 and extends downward therefrom, the neck having an elbow portion 23 from which extends a lateral outlet port 24, the terminal of the port structure being faced as a valve seat and inclined so that its lower portion protrudes slightly farther than its upper portion. The partition 19 has a duct 25 therein permitting the fuel in the upper chamber to descend into the middle chamber. When setting the vacuum tank 30 on a motor vehicle, the arrangement must be such as to permit the outlet port of the middle chamber to be directed towards the rear of the automobile. The wall of the neck 22 has a controller box 26 thereon in which is an inclined bore 27 that extends from the neck wall upwardly, being approximately at right angles to the face of the port. A gravity-valve 28 is arranged on the face of the port and is connected to a pivot 29 supported by the upper portion of the wall of the port, and the valve has a finger 30 thereon which extends into the bore 27 and is engaged by a weight ball 31 freely guided in the bore when the vacuum tank is tilted 45 backward as a result of the vehicle ascending a hill, to counteract the tendency of the valve 28 under such circumstances to swing open and possibly reduce the vacuum in the upper chamber of the tank.

50 Preferably the upper portion of the vacuum tank has an annular expansion chamber 32 on the outer side thereof to which vent tubes 33 are connected that are connected also to the top portion 21 of the lower chamber, so that liquid in the lower chamber may rise or expand into the tubes.

55 A fuel-supply conduit 34 is connected with the head or top part 18 and extends to a reservoir (not shown), usually lower and 60 distant from the vacuum tank. Preferably a discharge pipe 35 is connected with the top part 18 and the conduit 34 and extends downwardly towards the wall 14.

65 The top part 18 has a central boss 36 integral therewith and a valve chest 37 con-

nected with the boss, the boss having a vacuum chamber 38 therein that is connected with a bore or suction duct 39 formed in the valve chest. A nipple 40 is screwed into the valve chest and has a suction duct 41 extending therethrough, and a suction conduit 42 is connected to the nipple and also in any desired manner with the intake manifold of the engine, being preferably connected directly with the mixing tube 6 of the carburetor or pipe leading to the intake manifold.

70 Preferably the vacuum tank is provided with a check-valve to prevent injury or damage by explosion which might result from back-firing of the engine. Accordingly the bore 39 has a valve seat 43 at the outer end of the chamber 38 to be engaged by a preferable

cup-valve 44 loosely arranged in the bore 39 and receiving a stop projection 45 on the 75 inner end of the nipple 40, the projection having ports 46 providing communication between the duct 41 and the bore 39, there being communication past the valve 44 with the chamber 38 through the valve seat when

80 the valve is drawn away from the valve seat by the engine suction, the valve being stopped against the projection. In case back-firing occurs the valve is forced against

85 the valve seat and closes communication with the vacuum chamber in which there may be an explosive gas. The top part 18 has a central port 47 extending down from the chamber 38, and a valve seat 48 in the port and facing downwardly. The boss 36 has a guide bore 49 vertically arranged therein above the chamber 38. A valve 50 is arranged to

90 operate on the valve seat 48 and it is fixed to a rod 51 that extends upward into the guide bore 49 and has a head 52 fixed thereon that may be stopped on the lower end of the bore and limit the movement of the valve 50 away from its seat. The valve 50 has a 95 downward-extending stem 53 fixed thereto for controlling the valve. A suitable float 54 is arranged in the upper chamber of the vacuum tank and has a yoke 55 on its top that is slidingly arranged in connection with the stem 53, permitting the yoke to be moved

100 upward into contact with the body of the valve 50, the yoke being limited in its downward movement on the stem by contact with a suitable head 56 on the stem, the head preferably being hook-like to permit easy connection with the yoke. The top of the boss 36 has an upward-extending annular valve

105 seat 57 that is concentric to the guide bore 49, and forming an equalizing-chamber. The boss has also ducts 58 and 59 adjacent to the inner side of the valve seat and connecting with the vacuum chamber 38. A disk or 110 pop-valve 60 is arranged to operate upon the seat 57, as a combined accelerator and resistance device, and it has a stem 61 that is guided in the guide bore 49, and may be en-

115

120

125

130

gaged by the head 52 to force the valve from its seat and to hold the valve in open position. A cap 62 is secured to the boss, covering the top of the boss and therewith forming a circulation chamber in which the pop-valve 60 operates. The arrangement is such that when the valve 50 is lowered from its seat the valve 60 is permitted to rest on its seat.

10 A vent-valve preferably is provided for the vacuum chamber and is suitably arranged and preferably has a valve chest 63 upon the top part 18 at a suitable distance from the boss 36 and having a duct 64 connected therewith that extends into the boss and upward into the chamber above the boss so as to have communication with the ducts 58 and 59 when the pop-valve 60 is unseated. The valve chest 63 is vertical and has a port 20 65 in the bottom thereof communicating with the vacuum chamber. A valve body 66 is vertically guided in the valve chest and it has a valve 67 on its lower end adapted to close the port 65, the valve preferably having a projection 68 thereon that extends through the port when the latter is closed. The upper portion of the valve body 66 preferably has a valve 69 thereon arranged to operate on an annular stop seat 70 arranged 30 in the valve chest 63. The top part 18 has a conduit 71 therein extending from the lower portion of the valve chest 63, and also a duct 72 connected with the conduit 71 and the chamber 32, the conduit 71 being open 35 to the atmosphere, preferably through a goose-neck 73 connected therewith to exclude dust.

In order to guard against the valve 66 sticking to its seat, in some cases the top 40 part 18 is provided with a hanger 74 adjacent to the port 65 and a cam 75 is pivoted thereto beneath the projection 68 on the vent-valve, the cam having a rod 76 fixed thereon that is controlled by having suitable connection with the body of the valve 50, the body having a circumferential groove 55 77 into which the rod 76 extends, the arrangement being such as to enable the float in its upward movement to cause operation 50 of the cam so as to start and lift the valve 67 from its seat and insure admission of air into the vacuum chamber at the proper time.

In some cases a valve chest 78 is arranged 55 in the boss 36 and has communication through a duct 79 with the chamber in the cap 62, shown in Fig. 6, the bottom of the valve chest having a port 65' extending to the vacuum chamber, the valve body 66 being arranged in the valve chest and having the 60 valves 67 and 69, the latter being stopped against a ring or seat 71 fixed in the valve chest, the conduit 71 extending to the lower portion of the valve chest, such being a compact arrangement when it may not be necessary to force the vent-valve from its seat.

Or, the valve 50 may be adapted to extend under the projection 68 whereby to unseat the valve 67.

In practical use, the float chamber having been supplied with gasoline or other liquid 70 fuel, the engine may be started and supplied through the carburetor with fuel, the engine causing suction through the suction conduit 42. The float 54 being suspended in the vacuum tank chamber and holding down the valve 50, suction occurs through the port 47 and causes the formation of vacuum in the upper or vacuum chamber, the valves 60 and 67 being seated and preventing entrance of atmospheric air. The lower chamber 80 in the vacuum tank being vented, the liquid is permitted to be drawn into the carburetor. The valve 28 excludes the atmospheric air from the middle and upper chamber, and when the air is drawn out 85 from the chambers the vacuum occurs therein, the fuel is drawn through the conduit 34 and discharged into the upper chamber, the fuel flowing through the aperture 25 into the middle chamber. When the weight of 90 the liquid accumulating in the upper chamber becomes sufficient to open the valve 28 the liquid flows into the lower chamber and is fed as needed to maintain a proper level in the float chamber or reservoir of the carburetor.

In case the motor vehicle travels up hill the tendency of the valve 28 to swing open is counteracted by the weight ball 31 while the operation of supplying the upper chamber with fuel is continued, a considerable 100 volume therein causing the valve 28 to release a sufficient quantity of fuel to supply the lower chamber so that the valve 28 is sealed by the liquid which prevents the atmospheric air from passing to the valve. 105 When the liquid in the vacuum chamber rises and lifts the float 54 the yoke 55 is carried up to the body of the valve 50 and may move the valve until the head 52 closes the space above it and engages the stem 61, operating the cam 75 if present in the structure, to later dislodge the valve 67 from its seat. 110 While the suction through the ducts 58 and 59 strongly tends to hold the relatively large valve 60 to its seat, the suction still occurring past the valve 50, the upward movement of the float is momentarily arrested, but as the liquid rises still farther in the vacuum chamber the buoyancy of the float is increased and it is forced upward and causes the pop-valve 115 60 to be suddenly forced from its seat, in some cases the action causing a hammer-blow by the head 52 against the stem 61. The valve 50 having become suddenly seated and the pop-valve 60 opened, suction occurs 120 through the ducts 58, the chamber in which the pop-valve 60 operates, and through the conduit 64, resulting in the valve body 66 being mechanically lifted and then drawn upward and held by the suction, so that the 125

130

valve 67 opens the port 65 and later admits atmospheric air into the vacuum chamber. As the fuel is drawn off and fed to the carbureter the float descends a short distance 5 while the suction holds the valve 50 in closed position until the yoke on the float engages the head 56 on the valve stem and draws the valve 50 slightly downward, permitting the pop-valve 60 to become seated 10 suddenly by suction and held closed by the force of the suction, the valve 60 in its descent pushing the valve 50 completely from its seat, while suction again occurs through the port 47, the valve body 66 having been 15 freed and gravitating downward and carrying the valve 67 to its seat. The operations are repeated automatically and a proper supply of fuel maintained.

What I claim as new is:—

- 20 1. A vacuum-controlled fuel-supply system including a vacuum tank, a suction conduit having connection with the tank, a main valve in the tank to close the conduit, a buoyant device in the tank having a connection to move the valve to close the conduit, and resistance means effective to temporarily arrest the closing operation of the valve and subject to suction in the conduit and to a greater degree than the main valve.
- 25 2. A vacuum-controlled fuel-supply system including a vacuum tank, a suction conduit having connection with the tank and provided with a suction-cut-off valve and a relatively larger and flat faced resistance 30 valve and seat having a quick-action pop-valve character, the valves co-operating and subject to suction in the conduit to effect intermittent sudden closing and opening of the conduit, and a buoyant device to move 35 the suction-cut-off valve.
- 40 3. A vacuum-controlled fuel-supply system including a vacuum chamber, a fuel-supply conduit and a suction conduit connected with the chamber, a main valve to intermittently close the suction conduit and adapted to be removably held by suction in closed position, a variably-buoyant float loosely connected with the main valve to control its operation, and a diametrically larger suction-closed quick-action type pop-valve constructed and arranged to resist and momentarily arrest closing operation by the main valve and suddenly yielding under increasing buoyancy of the float.
- 45 5. A vacuum-controlled fuel-supply system including a vacuum chamber, a suction conduit having connection with the chamber, a main valve movable in the chamber to be seated to close the conduit, a buoyant device in the chamber connected with the main valve to move the valve to partially open the conduit, and a diametrically larger suction-closed quick-action type valve constructed and arranged to suddenly and fur-

ther move the main valve to fully open the conduit.

65 5. A vacuum-controlled fuel-supply system including a normally vertical vacuum tank with two chambers therein arranged one above the other and also a middle chamber connected with the upper one of the two chambers, the middle chamber being provided with an outlet to the lower one of the two chambers having an automatically-acting valve responding to liquid-pressure, and adjustably movable means adapted to automatically act, when the tank leans in one direction from the vertical, to increase the resistance of the valve to the liquid pressure.

70 6. A vacuum-controlled fuel-supply system including a normally vertical vacuum tank with two chambers therein arranged one above the other, the lower one of the chambers having a middle chamber therein and in direct connection with the uppermost one of the chambers, the middle chamber being provided with a controlling valve adapted to automatically permit downward flow of liquid responsive to varying column pressure, and means automatically acting on the valve, when the tank leans in one direction from the vertical, to variably increase the resistance of the valve to increasing column pressure.

75 7. A vacuum-controlled fuel-supply system including a normally vertical vacuum tank having an upper chamber and a vented lower chamber and also a middle chamber connected together, the lower chamber being directly beneath the upper chamber, the middle chamber being within the lower chamber and provided with a controlling valve adapted to normally control downward flow of liquid and to prevent flow of air upward through the middle chamber, and adjustably movable compensating means automatically co-operating with the controlling valve, when the tank is tilted in one direction from the vertical to variably load the valve and restrain normal operation thereof whereby to prevent upward flow of air into the upper chamber.

80 8. A vacuum-controlled fuel-supply system including a vacuum chamber having a head provided with a suction conduit having a port connected with the chamber, the head having a suction-equalizing chamber and a plurality of ducts connected therewith and with the suction conduit, a float-controlled main valve arranged for closing or opening the port and having a rod thereon extending towards the suction-equalizing chamber, and a quick-action type pop-valve covering the suction-equalizing chamber and removably held by suction through said ducts to resist closing operation by the main valve, the pop-valve having a materially greater diameter

125

than the main valve and a stem to be engaged by the rod on the main valve to instantly force the pop-valve from place.

9. A vacuum-controlled fuel-supply system including a vacuum chamber provided with a suction conduit having a downward-extending port connected with the chamber and an upward-extending port provided with a relatively large diameter pop-valve seat facing upward, the seat having an inclosing chamber, a vent-valve for the vacuum chamber having a duct connected with the inclosing chamber, a quick-action type pop-valve to operate upon the pop-valve seat, a main valve that is diametrically smaller than the pop-valve to close the downward-extending port and having a rod thereon arranged to engage and be stopped by the pop-valve and to suddenly lift the pop-valve in advance of closing action of the main valve, and a float in the vacuum chamber loosely connected with and controlling the main valve.

10. In a fuel-supply system for explosion engines, the combination with a suction conduit, a main valve to close or open the conduit, and a buoyant device operatively connected with the main valve, of a combined resistance and accelerating valve of the quick-acting popping type acting with greater force than the main valve under the influence of suction to momentarily resist closing movement of the main valve or to accelerate the opening movement of the main valve.

11. In a fuel-supply system for explosion engines, the combination with a vacuum tank, of a suction conduit extending to the vacuum tank, a main valve in the tank to close or open the end of the suction conduit, a buoyant device having loose operative connection with the main valve and normally moving the valve slowly and partially from the end of the conduit, and means including a relatively larger valve automatically operating on the main valve adapted to accelerate its movement to completely open the conduit following its initial opening movement.

12. In a fuel-supply system for explosion engines, the combination with a vacuum tank, of a circulation chamber, a suction conduit leading to the vacuum tank, suction ducts connected with the suction conduit and the circulation chamber, a main valve arranged in the vacuum tank to close or open the suction conduit, a buoyant device to float in the vacuum tank connected with and controlling the main valve, and a resistance valve having greater covering area than the main valve arranged in the circulation chamber to close or open the ducts and provided with connections enabling the resistance valve influenced by suction in the ducts to momentarily hold open the main valve and

thereby retard rising of the buoyant device and enabling the device to suddenly force the main valve to closed position.

13. In a fuel-supply system for explosion engines, the combination with a vacuum tank, of a circulation chamber having an upwardly-projecting annular valve seat therein to constitute an equalizing-chamber, a suction conduit leading to the vacuum tank, suction ducts connected with the suction conduit and the equalizing-chamber, a main valve arranged to close or open the suction conduit in the vacuum tank and having a rod thereon extending towards the equalizing-chamber, a buoyant device loosely connected with and operating the main valve, and a quick action type of pop-valve in the circulation chamber having larger diameter than the main valve to be suddenly drawn to the valve seat by suction through the ducts and the equalizing-chamber and having a stem thereon arranged to strike and push said rod and quickly force the main valve away from the suction conduit following unseating of the main valve.

14. In a fuel-supply system for explosion engines, the combination with a vacuum tank wall, of a head fixed upon said wall and having a vacuum chamber therein and also a suction conduit extending to the chamber, the head being provided with a port extending downward from said chamber to the under side of the head, the head having also a guide bore extending downward from the top thereof in alignment with said port and ducts extending from the vacuum chamber to the top of the head adjacent to said bore, an annular valve seat extending upward from the top of the head concentric to said bore and forming an equalizing-chamber into which said ducts extend, a pop-valve to co-operate with said seat to cover said ducts and said bore and having a stem extending downward into and guided in said bore, a main valve that is smaller than the pop-valve arranged at the lower end of said port to co-operate therewith and having a rod thereon extending upward into said bore, the rod being provided with a head to be moved to the bottom of the bore or to said pop-valve stem, there being a space between said stem and said rod head when the main valve is open and the pop-valve closed, and a buoyant device operatively connected loosely with the main valve.

15. In a fuel-supply system for explosion engines, the combination with a vacuum chamber and a suction conduit extending thereto, of a main valve in the chamber to close or to open the end of the suction conduit, a buoyant device having limited slipping connection with the main valve ultimately to move the valve to partially open the conduit, and means including a quick-action pop-valve that is diametrically larger

than the main valve and adapted to suddenly strike and completely unseat the main valve to fully open the conduit.

16. A vacuum-controlled fuel-supply system including a vacuum tank provided with a liquid-supply connection and a suction conduit, a float in the tank, a conduit cut-off valve and a vent valve actuated by the rise of the float to close the suction conduit and 10 to open the vent valve, and resistance means subject to suction in the conduit and to a greater degree than the cut-off valve to momentarily arrest the closing of the conduit.

17. In a fuel-supply system for explosion engines, the combination with a main vacuum chamber wall, of a head upon the wall provided with a horizontal vacuum chamber and a main suction conduit section connected therewith, the head having also a 20 central port extending downward from said horizontal chamber to the under side of the head and a guide bore vertically arranged above said horizontal chamber in alignment with the central port, the guide bore having a closure in its upper portion, a main valve 25 arranged to close the lower end of the central port, a rod fixed to the main valve and extending upward through said horizontal chamber and into said guide bore and having a head fixed to its top to contact with the bottom of the bore on downward movements of the main valve, and buoyant means loosely connected with the main valve to move and control the valve.

18. In a fuel-supply system for explosion engines, the combination with a main vacuum chamber wall, of a head upon the wall having a horizontal vacuum chamber therein and a main suction conduit extending 30 to the chamber and also a central port

extending downward from said horizontal chamber, the head having a vertical guide bore above said horizontal chamber in alignment with the central port and also an annular upstanding valve seat extending about 45 the top of the guide bore and ducts arranged adjacent to the guide bore and extending from said horizontal chamber to the space inclosed by said valve seat, a cap on the head covering said valve seat, a main valve arranged to operate in the lower end of the central port and having a guide rod thereon extending upward into said bore with means to operate and control the valve, and a pop-valve arranged to operate upon said valve 50 seat and therewith constitute an equalizing-chamber, the pop-valve having a stem fixed thereto that is guided in the guide bore to engage or be engaged by said guide rod.

19. In a fuel-supply system for explosion engines, a vacuum tank provided with a liquid-supply connection, a suction conduit connected with the tank, an air vent port, a vent valve for closing said port, a float in the vacuum tank, a cut-off valve directly 60 actuated by the rising of the float to close the vacuum conduit, a resistance valve having a materially greater area than the cut-off valve to momentarily arrest closing movement of the cut-off valve, the cut-off valve 65 operating finally to unseat the resistance valve by the rising of the float, and positive means controlled by the rising of the float operating to unseat the vent valve in advance of the closing of the cut-off valve and substantially coincident with the unseating of the resistance valve.

In testimony whereof, I affix my signature on the 12th day of December 1922.

MARTIN C. BRIGHT.
